US0D1037600S

(12) **United States Design Patent** (10) **Patent No.:** **US D1,037,600 S**
(45) **Date of Patent:** **** Jul. 30, 2024**

(54) **LIFTING DEVICE FOR INVALIDS**

(71) Applicant: **Arjo IP Holding AB**, Malmo (SE)

(72) Inventors: **Marie-Eve Boisclair LaBrie**, Waterloo (CA); **Marie Lafontaine-Lacasse**, Bromont (CA); **Samuel Desprez**, Bromont (CA); **Urban Orrell**, Bromma (SE); **Erwan Pouliquen**, Magog (CA); **Jessica Samson**, Sherbrooke (CA)

(**) Term: **15 Years**

(21) Appl. No.: **35/518,993**

(22) Filed: **Nov. 11, 2022**

(80) **Hague Agreement Data**

Int. Filing Date: **Nov. 11, 2022**

Int. Reg. No.: **DM/224867**

Int. Reg. Date: **Nov. 11, 2022**

Int. Reg. Pub. Date: **Nov. 17, 2023**

(51) **LOC (14) Cl.** **12-05**

(52) **U.S. Cl.**

USPC **D34/28**; D24/183
